APPARATUS FOR POINTING CORNERS

Howard C. Underwood and Edward B. Roby,
New York, N. Y.

Application June 8, 1934, Serial No. 729,558

6 Claims. (Cl. 223—2)

Among the principal objects which the present invention has in view are: To provide an apparatus having means thereon to eliminate the bulging or overlapping portion of material of the corner of a garment and the like; to provide means which will push inwardly the projecting end of a corner of a garment and the like; to enable the pointed corner of a collar to assume a uniform thickness and neatness in appearance; to apply heat to the garment and the like simultaneously with the performance of pushing the projecting end inwardly; and to secure simplicity of construction and operation.

In the drawing:

Figure 1 is an elevation of an apparatus embodying the features of the present invention;

Figure 2 is a top plan of the same shown as taken on the line 2—2 of Figure 1;

Figure 3 is a sectional view in part shown as taken on the line 3—3 of Figure 2;

Figure 4 is a sectional view shown as taken on the line 4—4 of Figure 2;

Figure 5 is a plan view of a collar in part showing one corner of the collar as projecting outwardly;

Figure 6 is a similar view and showing the projecting end of the corner of the collar pushed in and under the folded margin end; and

Figure 7 is a sectional view of the same shown as taken on the line 7—7 of Figure 6.

As seen in the drawing, attention is called to the fact that we utilize an apparatus having a standard 15 terminating in a head 16 providing for a vertical slideway 17 for a plunger 18. The standard furthermore provides a bed 19 positioned below and away from the plunger and adapted to support a forming die 20, and the plunger 18 carries a pressure die 21 for exerting pressure on the forming die with a garment or the like in place thereon. Operation of the pressure die 21 is obtained by any suitable means (not shown) but conveniently by employment of the means as illustrated in Patent No. 1,934,209 of November 7, 1933. However, such a means may conveniently be connected to a second class lever 22, an intermediate part of which engages the upper end of the plunger 18. One end of this lever may have suitably connected to it, a link 23, by which power is applied, whereas the other end is fulcrumed as at 24 in a bracket 25 forming part of the head of the apparatus. Preferably lever 22 provides a long arm between the plunger 18 and the connection of the link 23, and provides a short arm between the plunger and the fulcrum 24, so that a moderate pressure exerted by the operator may

apply a considerable pressure to the plunger and the pressure die 21 and the forming die 20. The lower end of link 23 is shown pivoted in a first-class lever 26 pivoted at 27 and forming part of the power applying means to the treadle (not shown) in accordance with the illustration of Patent Number 1,934,209 aforesaid.

Preferably the forming die 20 is composed of a relatively fixed die section 28 secured as by bolts 29 to the bed 19 and providing a forward face 30 against which the end edge of a collar or the like 31 may be brought into engagement while resting flatwise on the bed. The said forming die furthermore provides a slidable die section 32 which likewise rests upon the bed and may slide toward and away from the fixed die section 28 normal to the said face 30. The slidable die section has an end face 33 normal to the bed and at an acute angle with respect to face 30 corresponding to the desired angle of the intersecting edges of the garment or collar being formed.

In order to slide this slidable die section 32, the same is shown as having a guiding tongue 34 passing through a corresponding slot in the fixed die section 28. A compression spring 35 is positioned within a suitable socket, a part 36 of which is within the slidable die section and a part 37 of which is within the fixed die section, said parts of the socket being aligned and thereby enabling the spring to be positioned therein and force the slidable die section normally away from the fixed die section.

A suitable cam is provided to counteract the spring action and move the slidable die section 32 toward the fixed die section 28. As here shown, one example of such a cam comprises a stem 38 slidable axially parallel to the direction of movement of the plunger 18. Said stem passes vertically through the fixed die section, the tongue 34 of the slidable die section and through the bed 19. The part of the stem which passes through these several elements when in normal position, is of reduced diameter thereby providing a shank 39 loosely traversing said elements and forming a stop to limit outward movement 40 of the slidable die section as clearly shown in Figure 4.

As the stem 38 is lowered, a tapered enlargement 49 thereof enters the several holes in the fixed die section 28, slidable die section 32, and bed 19, causing said holes to become axially coincident by virtue of the enlargement 49 tapering to a full diameter of the stem equal to the diameter of the holes. The slidable die section is accordingly moved rearwardly. This move- 55

ment is preferably obtained by depression of the same treadle which operates the plunger 18, and as here shown, the lower end of stem 38 extends laterally as at 41 and is engaged in the end of first-class lever 26. This construction is illustrative of any suitable means for securing simultaneous operation of the slidable die section and the pressure die 21. It may further be noted that the upper end of the stem 38 may be steadied and guided by passing through a bracket 42 fixed upon the fixed die section 28.

The sloping face 33 of the slidable die section 32 next the corner thereof toward the fixed die section 28 is provided with a protruding lip 43, said lip being flatwise with respect to the bed 19 and slightly elevated above the same to permit a folded thickness of the garment material to enter thereunder.

It is very usual, in formation of acute-angle corners in garments for the hem or fold to present an undesired protrusion of the material, as shown in Fig. 5, and in operation of the apparatus above described, that protruding portion of material is engaged by the lip 43, and when the lip is slid, is thereby forced inwardly of the edge of the garment, as shown in Figure 6. When once forced in, this corner of the material remains tucked in, particularly since the pressure die 21 is also functioning, preferably with a simultaneous application of heat, upon the corner of the garment. The pressure die 21 is, however, notched, as at 44 so as not to overlie the tongue but so close thereto as to enable the applied pressure to be effective upon the tucked-in portion of the material.

We claim:

1. An apparatus as characterized comprising a forming die having a fixed section and a slidable section, said slidable section having a laterally protruding lip thereon directed toward the fixed section, a compression die, said lip being spaced from the lower face of the slidable section and the compression die having a recess to receive said lip throughout its height, and means for actuating the slidable section of the forming die and causing said lip to approach and effect a pressure toward the fixed section in use.

2. An apparatus as characterized comprising a forming die having a fixed section and a slidable section, said slidable section having a laterally protruding lip thereon directed toward the fixed section, a compression die, said lip being spaced from the lower face of the slidable section and the compression die having a recess to receive said lip throughout its height, and a cam for actuating the slidable section of the forming die and causing said lip to approach and effect a pressure toward the fixed section in use

3. An apparatus as characterized comprising a forming die having a fixed section and a slidable section, said slidable section having a laterally protruding lip thereon directed toward the fixed section, a compression die, said lip being flatwise

and elevated from the lower face of the slidable section and the compression die having a cut-out portion to receive the lip throughout its height, and a longitudinally movable stem having a cam portion for actuating the slidable section of the forming die and causing said lip to approach and effect a pressure toward the fixed section in use.

4. An apparatus as characterized comprising a forming die having a fixed section and a slidable section, said slidable section having a laterally protruding lip thereon directed toward the fixed section, a compression die having a notch corresponding to the said lip for avoiding direct engagement therewith, and means for actuating the slidable section of the forming die and causing said lip to approach and effect a pressure toward the fixed section in use.

5. An apparatus as characterized comprising a standard having a bed providing a forming die thereon, said forming die having a fixed section and a slidable section, said slidable section having a laterally protruding lip thereon directed toward the fixed section, a compression die having a cut-out portion corresponding to the said lip for avoiding direct engagement therewith, means for actuating the slidable section and causing said lip to approach and effect a pressure toward the fixed section in use, said means comprising a longitudinal stem parallel to the standard and having a reduced portion approximately midway thereof for non-actuation of the slidable section and an enlarged portion adapted to slide the slidable section toward the fixed section, with said stem passing through said sections and bed, and means for actuating simultaneously the said stem and compression die.

6. An apparatus as characterized comprising a standard having a bed providing a forming die thereon, said forming die having a fixed section and a slidable section, said slidable section having a laterally protruding lip thereon directed toward the fixed section, a compression die having a cut-out portion corresponding to the said lip for avoiding direct engagement therewith, means for actuating the slidable section and causing said lip to approach and effect a pressure toward the fixed section in use, said means comprising a longitudinal stem parallel to the standard and having a reduced portion approximately midway thereof for non-actuation of the slidable section and an enlarged portion adapted to slide the slidable section toward the fixed section, with said stem passing through said sections and bed, and means for actuating simultaneously the said stem and compression die, and said slidable section and fixed section having means whereby the slidable section is normally kept out of engagement with the fixed section when the enlarged portion of the stem is out of registration with the said sections and bed.
